US00D336291S

United States Patent [19]

Shimose

[11] Patent Number: Des. 336,291

[45] Date of Patent: ** Jun. 8, 1993

[54] **UNITARY VIDEO CASSETTE RECORDER
AND TELEVISION RECEIVER**

D. 306,856 3/1990 Shimose et al. D14/129
D. 310,363 9/1990 Shim D14/129
D. 310,522 9/1990 Yang D14/129
D. 324,517 3/1992 Barbieri ..... D14/126 X

[75] Inventor: Norihiko Shimose, Ehime, Japan

Primary Examiner—Theodore M. Shooman
Attorney, Agent, or Firm—Sughrue, Mion, Zinn,
Macpeak & Seas

[73] Assignee: Matsushita Electric Industrial Co.,
Ltd., Osaka, Japan

[57] CLAIM

The ornamental design for a unitary video cassette recorder and television receiver, as shown.

[**] Term: 14 Years

DESCRIPTION

[21] Appl. No.: 731,100

[22] Filed: Jul. 17, 1991

[30] Foreign Application Priority Data

Jan. 23, 1991 [JP] Japan 3-1418

[52] U.S. Cl. D14/129

[58] Field of Search D14/113, 124-134;
358/60, 237-239, 254-255
